UNITED STATES PATENT OFFICE.

JOSEPH WILLIAM SHEAN, OF SPEARVILLE, KANSAS.

AUTOMATIC GATE MECHANISM FOR RAILWAY CROSSINGS.

Application filed January 7, 1926. Serial No. 79,640.

This invention relates to an automatic gate mechanism for railway crossings and has for its primary object to provide such a mechanism wherein pairs of gates at opposite sides 5 of the railway track will be automatically moved into closed position whenever a train approaches the crossing in either direction, and this in a simple but yet highly efficient operating manner.

10 A still further and important object is to provide a mechanism that may be installed without great expenditure and without requiring the employment of skilled labor.

With the above and other objects in view 15 as the nature of the invention will be better understood, the same comprises the novel form, combination and arrangement of parts hereinafter more fully described, shown in the accompanying drawings, and claimed.

20 In the drawings wherein like reference characters indicate corresponding parts throughout the several views:

Figure 1 is a top plan view of my improved automatic gate mechanism wherein is 25 clearly disclosed the electric wiring diagram necessary in the successful operation of the mechanism.

Figure 2 is a side elevation of the mechanism.

30 Figure 3 is a detail vertical section of one of the gate arm supporting posts within which is the operating mechanism for the arm for moving the same from vertical to horizontal position, and vice versa.

35 Figure 4 is a similar vertical section taken at right angles through the post shown in Figure 3.

Figure 5 is a fragmentary section through a train engine cab floor and to a third rail 40 construction, the latter comprises essential elements of the invention, the floor being equipped with manually controlled contact means for engaging said third rail, said means being disclosed in side elevation, and

45 Figure 6 is an enlarged perspective of one of said manually controlled contacts.

Now having particular reference to the drawing, there is shown in Figure 1 a highway designated A, that crosses a railroad 50 track B, the rails of which are designated c—c.

In carrying out my invention there is installed in the trackway directly intermediate the rails c—c a third rail designated generally 55, that includes an inverted T-shaped in-

sulating rail 6 which is secured to the usual rail supporting ties. A metallic bar 7 is disposed directly upon the upper edge of said insulating inverted T-shaped rail, as shown in Figure 5.

The invention further constitutes the provision of pairs of gate arm supporting posts disposed upon opposite sides of the trackway B and upon opposite sides of the roadway A, each of said posts being vertically disposed as clearly shown in Figure 2, and being designated by the numeral 8. Suitably journaled within openings in the opposed side walls of each post 8 and arranged parallel with the roadway A is a shaft 9, the inner end of which projects through the adjacent side wall of the post, and carries a gate arm 10. Each shaft 9 carries a spur gear 11 that meshes with teeth 12 of a vertically slidably disposed rack bar 13 of relatively great 70 weight guided for vertical movement within suitable bearings 14—14, as shown in Figures 3 and 4.

Supported upon a suitable platform 15 within each hollow post is a heavy duty electric motor 16, one end of the armature shaft of which is equipped with a relatively large spur gear 17 that also meshes with the teeth 12 of the rack bar 13 in order that a rotation 80 of the motor in one direction will cause the raising of the arm which movement will cause a rotation of the shaft 9 in such a direction as to swing the gate arm downwardly into position horizontally above the roadway A as shown in Figure 2.

Also mounted within each hollow post 8 directly above the rack bar 13, and in spaced relation therewith when the same is in its lowered position is an electro-magnet 18, the source of electric supply for said magnet and said motor 16 being hereinafter described.

In Figures 2 and 5, the reference character 19 designates an engine cabin floor that is provided with a suitable opening 20 directly above the third rail 5 between the rails c—c of the trackway B. Pivoted to the underside of said floor at opposite edges of the opening 20 and extending upwardly through the opening at their upper ends are pivoted handle levers 21—21 that carry at their upper ends conventional detents 22—22 for cooperation with toothed segments 23—23 secured upon the floor board for maintaining the levers in various adjusted positions. The lower end of each lever 21 is forked as at 24, in Figure 110

6, and rigidly secured therein and insulated from the fingers of the forks is a metallic contact plate 25 that carries at its rear side a wire securing jack 26.

5 As more clearly shown in Figure 5, the contact carrying ends of the levers 21—21 extend downwardly at opposite sides of the third rail 5 and are normally maintained in the out of contact position as shown in this 10 figure. By swinging the levers 21—21 upon their pivots in a certain direction, said contact 25 will engage the bar 7 of the rail 5 in a manner and for a purpose hereinafter 15 to be more fully described.

15 Suitably disposed in the engine cab is a storage battery 27, one pole of which is electrically connected with one of the axles D of the engine, Figures 1 and 2 while the other pole thereof has separate electrical connection with the jacks 26 of the lever carrying 20 contact 25.

25 The rails c—c of the trackway B are electrically connected to said contacts of the motors 16 and electromagnets 18 within the posts 8, while the other contacts of said motors and electromagnets are electrically connected to the third rail 5, it being noted that the motors and magnets in the posts upon both sides of the track way are connected to 30 the rail c and sides of the third rail 5 adjacent these posts for the obvious purpose of permitting the gate arms of each pair of posts to be swung downwardly in unison.

35 Associated with each motor 16 is a cut out switch that includes a pivotal plate 28 that is adapted to be engaged by a pin 29 carried by each rack bar 13 after the same has been moved upwardly to such an extent as to draw its corresponding gate arm 10 in the downward horizontal position as shown in Figure 40 2 for thus cutting out the circuit to the particular motor for preventing further operation of the same.

45 The third rail 5 extends a great distance beyond opposite sides of the roadway A and it will be obvious that upon the engagement of the lever contacts 25—25 with the bar 7 of the rails, the circuit will be completed to the battery to the motors 16 and electromagnets 18.

50 Each rack bar 13 upon reaching its upward limit of movement will engage its respective

electromagnets and be held in the upward position thereby. As soon as the train passes beyond the third rail 5 the circuit will be broken and the weight of the bars 13 will cause the same to drop and consequently raise the gate arm 10 to the normal vertical position as more clearly shown in Figure 4.

55 It will thus be seen that I have provided a highly novel, simple, and efficient form of 60 automatic gate mechanism for railway crossings that is well adapted for all of the purposes hereinbefore designated, and that may be installed in an easy and cheap manner and that is not liable to readily become out of 65 order.

Minor changes may be made therein without departing from the spirit and scope of the invention and appended claim.

Having thus described the invention, what 70 I claim as new is:—

In an automatic gate mechanism for railroad crossings, hollow posts at the crossing, each including a horizontally pivoted gate arm mounted for swinging movement on the outside of the post, a vertically sliding weighted bar arranged within each post and operatively connected with the arm whereby movement of the same in opposite directions will cause the swinging of the arms in opposite directions, an electric motor operatively connected to said bar for moving the same upwardly, said bar being adapted to move downwardly by gravity, an electric magnet in each hollow post supported above the slideable weighted bar and arranged in the same circuit with the motor, said electromagnet engaging the upper end of the bar for holding the same in a raised position for maintaining the swinging arm in a horizontal position, cooperating means between the electric motor and the slideable weighted bar for cutting off the electric motor automatically when the weighted bar is raised to a predetermined position, said last mentioned means comprising a switch associated with the electromotor, said switch including a pivoted plate and a trip carried by the weighted bar and adapted for engagement with the pivoted plate of the cut-out switch.

95 In testimony whereof I affix my signature.
JOSEPH WILLIAM SHEAN.
